CLAIM

The ornamental design for a payment terminal with wheelchair accessible mount, as shown and described.

DESCRIPTION

FIG. 1 is a perspective view of the payment terminal with wheelchair accessible mount;

FIG. 2. is a front side view of the payment terminal with wheelchair accessible mount of FIG. 1;

FIG. 3. is a rear side view of the payment terminal with wheelchair accessible mount of FIG. 1;

FIG. 4. is a right view of the payment terminal with wheelchair accessible mount of FIG. 1;

FIG. 5. is a left view of the payment terminal with wheelchair accessible mount of FIG. 1;

FIG. 6. is a top view of the payment terminal with wheelchair accessible mount of FIG. 1;

FIG. 7. is a bottom view of the payment terminal with wheelchair accessible mount of FIG. 1;

FIG. 8. Is a another perspective view of the payment terminal with wheelchair accessible mount of FIG. 1, shown in an extended position for use with the pull handle in a downward position for use; and,

FIG. 9. Is a another perspective view of the payment terminal with wheelchair accessible mount of FIG. 1 shown within its environment in an extended position for use with the pull handle in a downward position.

The broken lines in FIG. 3 depict parts of the payment terminal with wheelchair accessible mount that form no part of the claimed design.

(Continued)

The broken lines in FIG. 9 are for the purpose of illustrating environmental and form no part of the claimed design.
